LAWN SPRINKLER

Filed Sept. 6, 1927

UNITED STATES PATENT OFFICE.

MAX SCHNEIDER, OF DENVER, COLORADO.

LAWN SPRINKLER.

Application filed September 6, 1927. Serial No. 217,614.

This invention relates to improvements in lawn sprinklers and has reference more particularly to an improved sprinkler of the oscillating type.

For the purpose of irrigating lawns it is often desirable to employ a sprinkler that can be set on the ground and which will sprinkle an area whose size and shape can be varied. In sprinkling parkings the 10 sprinkler must cover a long narrow area; when sprinkling that portion adjacent the house the sprinkler should cover a semi-circular space when placed along one side of the house and when placed at one corner of 15 the house it should cover a sector shaped area of 270 degrees in extent. When large lawns are to be irrigated the sprinkler should cover a whole circle.

It is the object of this invention to produce 20 a sprinkler that can be so adjusted that it will irrigate sectors varying from a few degrees in width to a complete circle.

It is a further object of this invention to produce a sprinkler of the oscillating type 25 which shall be of simple and substantial construction, which can be cheaply made and which will not readily get out of order.

The above and other objects that may become apparent as this description proceeds 30 are attained by means of a construction and an arrangement of parts that will now be described in detail and reference for this purpose will now be had to the accompanying drawing in which one embodiment of 35 my invention has been shown and in which:

Fig. 1 is a top plan view of my improved 40 sprinkler,

Fig. 2 is a section taken on line 2—2, Fig. 1.

Fig. 3 is a section taken on line 3—3, Fig. 2 and shows the relationship of the deflector plate to the oscillating arm and,

Fig. 4 is a section corresponding to that 45 shown in Fig. 3 and shows a slightly modified construction.

In the drawing I have illustrated a base having a ring 5 that is adapted to rest upon the surface of the ground and to which the central body portion 6 is attached by means 50 of a plurality of radial arms or supports 7. The central body portion 6 has an opening 8 whose outer end 9 is threaded so that connection can readily be made between the sprinkler and the end of a hose. The inner end 55 of the opening 8 terminates in an upwardly extending portion 9 that is concen-

tric with the ring 5. The inner surface of opening 9 is threaded and receives the threaded end 10 of the pivot tube 11. This tube has an annular flange 12 whose lower 60 surface abuts the upper surface 13 of the base and whose upper surface serves as a support for the hollow hub 14 from which the tubular arm 15 extends. Hub 14 can be constructed in any suitable way but has 65 been shown as formed from a cup shaped member whose bottom 16 has a central opening through which tube 11 extends, and a cover 17, that is provided with a downwardly extending circular flange 18 which 70 has its outer surfaces formed with threads that engage corresponding threads in the upper end of the cylindrical side of the cup portion. Cover 17 has a central opening through which tube 11 extends. The holes 75 in the bottom 16 and in the cover 17 are of such size that they make a close fit with the tube, but permit free rotation of the hub. The upper end of tube 11 has a central threaded opening for the reception of the 80 threaded end 19 of the screw 20; this screw is provided with wings 21 and passes through the washer 22 and the two stops 23 and 24. The stops 23 and 24 are formed from metal bars having their outer ends 25 85 bent downwardly and of such length that they intersect the path of the radial tube 15 and limit its movement in both directions. By means of the screw 20 the stops 23 and 24 90 may be clamped in any position desired. 90 Tube 11 is also provided with several openings 26 through which water may flow into the interior of hub 14.

For the purpose of producing a force that 95 will cause the tube 15 to oscillate when water is flowing through it, I have provided it with a deflector plate 27 that is attached to the outer end of the tubular arm 15 by means of a pivot 28 whose axis is parallel with the axis of the tube 11. The deflector plate 100 27 has only a very short section 29 on the inside of the pivot while the part on the outside of the pivot point is quite long and wide. The end 29 is of the same width as the opening in which it is pivoted so that 105 when it is in the position indicated by full lines in Fig. 3 the end of tube 15 will be closed except for the opening 30 and therefore the water must flow out through this opening. The pressure of the water on the 110 surface of the end 29 will tend to hold the deflector plate in the position shown. The

water that flows outwardly through opening 30 strikes the surface of plate 27 and is deflected thereby producing a force that tends to move arm 15 from the full line to the dotted line position in Fig. 1. This force is sufficient to make tube 15 swing with considerable velocity and when it strikes the stop 23 the momentum of the plate 27 will make it move about its pivot from the full line to the dotted line position. The reaction of the water will now produce a force acting in the opposite direction and the arm 15 will swing about its pivot until it engages the stop 24 when its movement will cease abruptly thereby causing the deflector plate to swing about its pivot whereby the direction of the force will be again reversed. By means of the stops the arc through which the arm 15 swings can be adjusted to any extent desired. If both of the stops are removed the arm 15 will continue to rotate in the same direction as long as water is flowing.

In Fig. 4 I have shown a modification in which the plate 27 has been replaced by a tube 31 whose dimension in one direction is equal to the distance between the upper and lower sides of tube 15 but whose width c is less than the width d of the tube 15 so that tube 31 can move from full line to dotted line position and vice versa. The outer end of the tube 31 is closed and provided with a plurality of slots 32 through which the water will issue. The reaction of the water as it leaves the end of the tube 31 produces a force that makes the tube 15 swing about its pivot. When tube 15 stops suddenly the momentum will cause pivoted tube 31 to swing from full line to dotted line position or in the reverse direction, whereby the direction of the actuating force is also reversed.

From the above it will be apparent that I have produced a sprinkler in which the spray is moved back and forth over a sector of any extent and whose operating mechanism is of exceeding simplicity.

Having described the invention what I claim as new is:—

50. 1. In a sprinkler having a supporting base and a nozzle pivotally secured thereto, a stop surface located on each side of the nozzle, means comprising a deflector plate pivotally secured near its inner end to the outer end 55 of the nozzle for changing the direction of the water stream from one side of the axis of the nozzle to the other, said plate having its center of gravity between its outer end and its pivot point whereby its momentum will cause it to rotate about its pivot whenever the nozzle strikes one of the stops and means for limiting extent of the rotation of the deflector means.

2. A spray device comprising a base, a

hollow pivot secured to the base, means for 65 making connection between the interior of the pivot and a source of water under pressure, a tubular nozzle secured to the pivot by means which permits it to oscillate about the axis of the pivot, said pivot having an 70 opening whereby communication is provided between the interior of the pivot and the nozzle so that water can flow outwardly through the nozzle, a deflector plate attached near its inner end to the outer end of the 75 nozzle by means of a pivot substantially parallel with the pivot about which the nozzle oscillates, said plate serving as a means for deflecting the water stream so that it will flow in a direction at an angle 80 to the axis of the nozzle whereby a force will be produced that tends to rotate the nozzle about its pivot, said plate having its center of gravity between its free end and the pivot, and a stop located on each side of 85 the nozzle.

3. In a sprinkler having a supporting base and a nozzle pivotally secured thereto, a stop located on each side of the nozzle, a deflector plate secured to the outer end of 90 the nozzle by means of a pivot that is substantially parallel with the pivot about which the nozzle moves, the inner end of said plate extending into the tube a short 95 distance, said inner end being adapted to engage the inside of the tube so as to form a stop for limiting the oscillation of the plate about its pivot, the outer end of said plate extending outwardly beyond the pivot point to such a distance that the center of gravity 100 of the plate will lie some distance outside of the pivot about which the plate oscillates, whereby when the nozzle is suddenly brought to rest by striking one of the stops the plate will continue to move until it has 105 crossed the axis of the nozzle and occupies a position in which the inner end of the plate contacts with the opposite inside surface of the nozzle.

4. In a sprinkler having a supporting base 110 and a nozzle pivotally secured thereto, a deflector plate secured to the outer end of the nozzle by means of a pivot that is substantially parallel with the pivot about which the nozzle moves, the inner end of said plate 115 extending into the tube a short distance, said inner end being adapted to engage the inside of the tube so as to form a stop for limiting the oscillation of the plate about its pivot, the outer end of said plate extending 120 outwardly beyond the pivot point to such a distance that the center of gravity of the plate will lie some distance outside of the pivot about which the plate oscillates and stops carried by the base for limiting the oscillation of the nozzle.

In testimony whereof I affix my signature.
MAX SCHNEIDER.
